UNITED STATES PATENT OFFICE.

WILLIAM W. McEWAN, ARTHUR McEWAN, AND FRANK McEWAN, OF WHIP-PANY, NEW JERSEY, ASSIGNORS TO THE STONY BROOK PAPER COMPANY, OF SAME PLACE.

APPARATUS FOR MANUFACTURING FIBROUS ARTICLES FROM PULP.

SPECIFICATION forming part of Letters Patent No. 635,800, dated October 31, 1899.

Application filed April 13, 1899. Serial No. 712,922. (No model.)

To all whom it may concern:

Be it known that we, WILLIAM W. McEWAN, ARTHUR McEWAN, and FRANK McEWAN, citizens of the United States, residing at Whippley, Morris county, State of New Jersey, have invented certain new and useful Improvements in Apparatus for Manufacturing Fibrous Articles from Pulp, of which the following is a full, clear, and exact description.

10 Our invention relates to apparatus for manufacturing fibrous articles from paper-pulp; and the object of said invention is to provide a simple and efficient apparatus for producing at little cost fibrous articles wherein a 15 highly-effective surface ornamentation is produced by the natural formation of the pulp in the process of manufacture.

To these ends our invention consists in the apparatus hereinafter described and claimed, 20 reference being had to the accompanying drawings, wherein—

Figure 1 is a perspective view of an apparatus embodying our invention, parts of said apparatus being broken away to better illustrate the invention. Fig. 2 is a detail perspective view of one of the foraminous formers. Fig. 3 is a longitudinal sectional view of the same with the pulp shown adhering thereto, the view being taken on the line 33 25 of Fig. 2. Fig. 4 is a detail face view of the stirrer to be hereinafter described. Fig. 5 is a fragmentary perspective view of an article made in accordance with our invention. Fig. 6 is an enlarged sectional view of the same. 30 In Fig. 1 of the drawings is illustrated a vat A, which we term a "forming-vat." This vat has side walls a and a solid bottom b, and above this solid bottom is suitably supported a pulp-screen B, which preferably 35 consists of a lower layer of comparatively heavy wire-gauze c—say, for instance, what is known as "No. 14" gauze—which is capable of withstanding the pressure exerted upon the screen. Upon this first layer of 40 wire-gauze is supported one of a finer mesh, as indicated at d. This layer d is preferably what is known as "No. 30" wire-gauze. Communicating with the chamber formed between the screen B and the solid bottom of 45 the forming-vat is a suction-pipe e, which is connected to a suitable pump and may be controlled by a valve f. The suction-pipe e

may deliver to a suitable outlet, so that the water drawn therethrough will pass off, with what pulp may be contained therein, as a 55 waste product, or the suction-pipe may deliver the water back into the forming-vat. In practice we prefer the former course, inasmuch as the water when once used is not as clear as desired to produce the best results. 60

In Figs. 2 and 3 we have represented what we term a "foraminous" former C. Any suitable number of these formers may be employed, and they may be of any desired shape 65 and correspond in contour to the articles to be formed. These foraminous formers may be economically constructed with a body or frame g of wood, in which a series of channels h is cut. The top and sides of each of 70 these frames are covered with two layers i j of wire-gauze, the inner layer i being comparatively heavy and of a coarse mesh, while the outer layer j is of a finer mesh, as is the case in the construction of the screen B. The 75 lower edge of each of the formers is preferably surrounded by a deckle k, which will prevent the pulp from being deposited on the former at this point, so that the former with the pulp adhering thereto may be readily withdrawn from the screen without the necessity of separating the web of pulp on the former from that deposited on the screen B. The 80 deckles k may be variously formed on the edges thereof to give different contours to 85 the edge of the article, and when such deckles are employed there is ordinarily no necessity for finishing the edge of the article after it is removed from the former.

The bottom of each of the formers is adapted 90 to rest upon the screen B, as indicated in Fig. 1, and a communication is established through the screen between the channels in each of the formers and the suction-pipe e when the valve f is open. Water may be supplied to 95 the forming-vat through the pipe l, while thin pulp may be supplied to the vat through a pipe m. The pulp may be agitated by any suitable means, such as the stirrer D. (Shown in Fig. 4.) This stirrer is adapted to rest at 100 the ends thereof upon the sides of the vat A and may be moved along the vat by the handles o, care being taken that the stirrer-arms do not contact with the formers.

In operation the valve *f* is first closed and the forming-vat is filled with clear water until all of the formers are submerged. A sufficient quantity of previously-prepared thin paper-pulp is then admitted to the forming-vat through the pipe *m* and is agitated to thoroughly mix it with the water, so that the fibers may be held in suspension therein. The valve *f* is then opened and the water is withdrawn through the suction-pipe *e*, and a web of pulp will be drawn or deposited on the various formers and against the screen *B*, where no formers rest while the water is being drawn off. For the production of rough-faced articles care should be exercised that no forming-surface is brought into contact during the process of manufacturing the article with those portions of the surface of the pulp-web where the roughened surface is to appear, nor that those portions of the pulp-web be submitted to compression during or after the article is formed, so that the natural roughened surface of the article made by depositing the pulp on the formers will not be disturbed. The layer of pulp on the formers will, as indicated at *E* in Figs. 3 and 5 of the drawings, present a roughened outer surface which may be increased or decreased accordingly as the proportion of water employed is increased or decreased. The thickness of the layer of pulp is determined by the amount of pulp and water contained in the forming-vat or the length of time that the suction through the pipe *e* is maintained in action. After all the water has been drawn from the pulp the formers are taken out of the forming-vat, and the pulp on the formers may be allowed to dry and harden thereon without further treatment, so that the general contour of the formers will be given to the pulp and the natural roughened surface thereof will be set and will form a physical characteristic of the finished article. If desired, the pulp may be taken from the formers when they are withdrawn from the forming-vat and placed upon corresponding dummy formers to dry in order that the formation or foraminous formers may immediately be placed back in the vat and the forming operation repeated without further delay. However, where a sufficient number of foraminous formers have been provided we prefer to allow the pulp to remain thereon until dry and the article is completed, since a handling of the pulp is thus avoided and there is little if any liability of the surface being disturbed.

One of the characteristics of an article made in accordance with the above description is that the fibers lie in different directions, as we have indicated, by way of illustration, in Fig. 6 of the drawings. It will likewise be found in practice that the lowermost portions of the roughened surface are more compact than the elevated portions. The explanation of this is that the general tendency of the fibers in the lowest portions of the surface is to lie in directions substantially parallel to the

plane of the surface of the article, as indicated at *p* in Fig. 6, whereas the general tendency of those at the elevated portions of the surface is to lie at substantially right angles to the plane of the surface, as indicated at *q* in Fig. 6. This likewise explains why it is that the article is thicker in some places than others, so as to produce the roughened surface referred to herein. Thus in the course of manufacture fibers will be simultaneously deposited upon every exposed surface of the former. Some of these fibers will be deposited in planes substantially parallel to the surface of the article, while others will lie at substantially right angles thereto. Obviously the first-mentioned fibers will present a greater surface for resistance of the water passing through the pulp and former than the last-mentioned fibers and the water passing through those portions where there is the least resistance will deposit more fibers at these portions than at the others, and the weight of the water in the vat will compact the fibers at those portions of the article where the water does not pass through so freely. It will therefore be understood that any compression or surface pressure exerted by a forming-surface upon the pulp on the former during the course of manufacture or afterward or any shogging of the former during the course of manufacture will cause all the fibers to lie in planes substantially parallel to the surface of the article, thereby destroying the effect which has been described.

It is obvious that instead of depositing the pulp upon formers which give the finished contour to the article the pulp may be deposited upon a flat former or screen. The sheets of pulp so deposited may be afterward given the finished contour while the pulp is still wet and without disturbing the natural surface ornamentation thereof.

Having described our invention, what we claim, and desire to secure by Letters Patent, is—

1. In an apparatus for forming fibrous articles from pulp, the combination of a fixed flat supporting-screen, a plurality of removable foraminous formers adapted to be supported upon said screen and means for withdrawing fluid through said screen and foraminous formers.

2. In an apparatus for forming fibrous articles from pulp, the combination of a forming-vat having a supporting-screen above the bottom thereof, a plurality of removable foraminous formers adapted to be supported on the screen and means communicating with the vat below the screen for withdrawing fluid through said screen and foraminous formers
